ASSIGNORS TO WESTINGHOUSE ELECTRIC AND MANUFACTURING COMPANY, A
CORPORATION OF PENNSYLVANIA.

STARTING-ELECTRODE FOR VAPOR ELECTRIC DEVICES.

1,159,915.

Specification of Letters Patent.

Patented Nov. 9, 1915.

Application filed February 5, 1914. Serial No. 816,847.

To all whom it may concern:

Be it known that we, SIDNEY W. FARNSWORTH and OTTO P. SCHUSTER, citizens of the United States, and residents of Pittsburgh, in the county of Allegheny and State of Pennsylvania, have invented a new and useful Improvement in Starting-Electrodes for Vapor Electric Devices, of which the following is a specification.

10 Our invention relates to vapor electric devices such as rectifiers and lamps, and it has particular reference to starting or "keeping-alive" electrodes for metal-case rectifiers of high capacity.

15 One of the objects of our invention is to provide electrodes in which the adjustment made necessary by the occasional extinction of the arc is automatically effected.

20 A further object of our invention is to provide means, in addition to the automatic means, by which the initial position of the electrode may be manually adjusted.

25 A still further object of our invention is to supply a starting electrode with an indicator on the exterior of the casing which will clearly and positively show the position of the electrode.

30 In the accompanying drawing, which shows one embodiment of our invention, Figure 1 is a vertical sectional view of a portion of a metal-case rectifier equipped with our "keeping-alive" electrode; Fig. 2 is a plan view of the exterior portion of the electrode, the solenoid being omitted, and 35 Fig. 3 is a horizontal sectional view, taken on the line III—III, of Fig. 1.

35 Referring to Fig. 1 of the drawing, a portion of the casing 1 is shown and also a portion of the cover 2. An opening 3 in the cover is surrounded by a circular groove 4 in which is fixed a collar 5. A bushing 6 of porcelain or other suitable insulating material extends through the opening into the casing and is provided with an annular shoulder 7 which rests upon the cover, as shown. A second annular shoulder 8 engages the sides of the opening and serves to center the bushing therein. A washer 9 of asbestos or other suitable slightly compressible material rests upon the upper face of the shoulder 7, and, upon this washer, a metal bushing 10 is adapted to bear. The bushing 10 has a flange 11 the form of which is clearly shown in Fig. 2 and, as will be

apparent therefrom and from Fig. 1, the flange 11 is secured to the cover at several points by tap bolts 12. Spaces are left between the collar 5, the bushing 6 and the bushing 10 that may be filled with mercury to insure a hermetic seal between the bushing 6 and the cover 2. If desired, the shoulder 7 may be made thicker than is shown on the drawing, to elevate the washer 9 above the mercury seal.

40 The bushing 6 extends a considerable distance above the cover, and, near its top, it is provided with an internal annular seat 20 upon which a shoulder 21 of an internally threaded tubular member or terminal rod 22 is adapted to bear. The tubular member 22 terminates in a threaded rod 23 of reduced diameter, that is surrounded by a knob 24 or other suitable turning means. A metallic bushing 26 is secured to the top of the bushing 6 by means of a ring 27 of a 45 suitable cement. The bushing 26 is internally threaded, and a sleeve 28 is secured therein by means of a threaded collar 29 that is rigidly fixed to the sleeve. The sleeve 28 surrounds the threaded portion 23 50 of the tubular member 22 and extends nearly to the knob 24. A nut 46 is mounted to travel on the rod 23 and carries a pin 47 that projects through a slot in the sleeve 28, whereby the nut is prevented from turning, but is permitted to travel vertically when the rod 23 is turned by the knob 24. An opening 29a is provided in the collar 29 55 through which mercury may be introduced into the space between the bushing 6 and the tubular member 22. A suitable gum may be placed above the mercury to keep the latter from displacement. A spring 30 surrounds the tubular member 22 and presses at one 60 end against the shoulder 21 and at the other 65 end against the sleeve 28. A sleeve 31 encloses the spring, and keeps it from contact with the gum above the mercury seal.

65 Screwed into the tubular member 22 and extending into the lower part of the bushing 6, is a threaded rod 25 of magnetizable material having an enlargement 32 at its lower end. A frame 33 is suspended from the enlargement 32 and, through the bottom of this frame, projects a rod 35 of magnetizable material which terminates in an enlargement 36 similar to the enlargement 32. The rod 35 is capable of vertical move-

ment within the frame 33, the extent of its movement being so limited by a pin 37 as to prevent the two iron parts 32 and 36 from coming in contact and "freezing" by reason of permanent or residual magnetism. The movement is limited to a comparatively small distance because it has been found advantageous to keep the point of the electrode as near the surface of the mercury as practicable, thus giving a short, hot arc. The frame 33 may be formed of nickel, of copper plated with nickel, or of an alloy of nickel and iron having low magnetic permeability, and it is conveniently made of a strap of some such non-magnetic material, bent into the shape shown in Fig. 1.

Surrounding the bushing 6, at a point immediately outside of the frame 33, is a solenoid 38, which may be electrically connected in series with the circuit which energizes the starting anode 40. It will be observed from the foregoing description that the rods 25 and 35 perform the function of a divided magnet core and that, when the solenoid 38 is energized, these rods being of opposite polarity will tend to approach each other. Since, however, the rod 25 is fixed, the rod 35 will be lifted vertically as far as the pin 37 will permit. The rod or core section 35 is adapted to serve as a hanger for the electrode 40, through the instrumentality of a rod 41. The electrode 40 may be formed of carbon, tungsten, molybdenum or other suitable material and may be joined to the rod 41 by means of a connector 42 having an enlargement 43 at its lower end to support a sleeve 44 of quartz or other suitable insulating material which surrounds the rod 41. The vertical motion of the core section 35 causes the electrode 40 to be immersed in, and removed from, a pool of mercury 45 which forms the cathode of the rectifier, and the quartz sleeve 44 is held in a vertical position by a centering piece 48 that is mounted on a quartz ring 49 with which the cathode is surrounded.

In order to permit free passage of the current around the moving operating parts, a flexible connector or shunt 50 is disposed around the core-section 35 and connected to the frame 33 and to the rod 41 at its junction with the core section 35. The shunt 50 not only reduces the resistance within the rectifier but, by deflecting most of the current from the moving parts, prevents them from injury. The frame 33 may well be provided with a graphite bushing at the point where the rod 35 passes through it.

Before the rectifier is put in operation, the starting electrode 40 occupies its lower position shown in Fig. 1, in which position its end dips into the mercury cathode. Direct current is supplied to the starting electrode from any convenient source, such as a storage battery, a small motor generator set or

a small rectifier bulb auxiliary to the main rectifier. The solenoid 38 is also energized, since it is in series with the starting electrode, and the core section 35 is thus drawn upward, thereby raising the electrode 40 from the mercury cathode and drawing a starting arc of the desired length between these electrodes. The parts remain in this relation until the main arc is extinguished and the circuit thus broken. The solenoid, being no longer energized, releases the core section 35, and the electrode 40 drops back into mercury pool, thus re-establishing the circuit and energizing the solenoid, whereby the electrode is again drawn from the mercury pool and another arc established. It will thus be seen that the arc is automatically kept alive as long as the electrode 40, when in its lowest position, can dip beneath the surface of the mercury cathode. When, however, the end of the anode is burned away, so that further adjustment is desirable, this may be effected by turning the knob 24 and, consequently, the tubular member 22 in the proper direction to force the core section 25 farther into the vacuum chamber. This manual adjustment is necessary only at considerable intervals, and there is, therefore, little danger that the parts in frictional contact will be worn sufficiently to injure the hermetic seal and destroy the vacuum. Provision can easily be made for a much longer keeping-alive electrode than the one shown in the drawing, which would need to be replaced only at long intervals.

The frame 33 is prevented from rotating by the inner walls of the bushing 6 which are of elliptical form, as is clearly shown on Fig. 3.

It will be observed that the threaded rods 23 and 35 are of the same diameter and are similarly threaded. The movement of the nut 46 on the rod 23 corresponds, therefore, to the movement of the electrode 40, and the pin 47 consequently indicates the position of the electrode.

It is obvious that numerous modifications may be made in this device without departing from the spirit and scope of our invention, and therefore, we do not wish to be restricted to the precise structural details which we have shown and described, our invention being limited only by the scope of the appended claims.

We claim as our invention:

1. A vapor electric device comprising a casing, a vaporizable electrode and a starting electrode contained within the casing, automatic means for operating the starting electrode, and independent means for manually adjusting the position of the starting electrode.

2. A vapor electric device comprising a vacuum chamber, an electrode therein, and

means exterior to the chamber for indicating the position of the electrode.

3. A vapor electric device comprising a vacuum chamber, an electrode therein, means operated from the exterior of the chamber for varying the position of the electrode, and means exterior to the chamber for indicating the position of the electrode.
- 10 4. A vapor electric device comprising a vacuum chamber, a vaporizable electrode and a starting electrode contained in the chamber, means embodying a loose coupling for manually reciprocating said starting electrode, and electromagnetic means for also reciprocating said starting electrode and operating at said loose coupling.
5. A vapor electric device comprising a casing, an electrode within the casing, and 20 means extending into the casing for varying the position of the electrode, said means comprising a threaded rod from which the electrode is suspended, a turnable tubular member into which the rod is screwed, a bushing surrounding the tubular member

and having an internal annular seat, an annular shoulder formed on the tubular member and adapted to rest on the annular seat within the bushing, and means for producing a vacuum-tight seal between the 36 turnable tubular member and the bushing.

6. A vapor electric device comprising a casing, a movable electrode and a vaporizable electrode within the casing, automatic means controllable at a distance from the 35 casing for effecting a separation of the electrodes to a predetermined extent, and independent means for causing the movable electrode to approach the vaporizable electrode to compensate for the burning away of the 40 movable electrode.

In testimony whereof, we have hereunto subscribed our names this 30th day of Jan., 1914.

SIDNEY W. FARNSWORTH.
OTTO P. SCHUSTER.
